UNITED STATES PATENT OFFICE.

ABNER M. SEELEY, OF NEW YORK, N. Y.

RECORD-HOLDER.

No. 921,289.

Specification of Letters Patent.

Patented May 11, 1909.

Application filed February 10, 1905. Serial No. 245,032.

To all whom it may concern:

Be it known that I, ABNER M. SEELEY, a citizen of the United States, residing in the city, county, and State of New York, have 5 invented certain new and useful Improvements in Record-Holders, of which the following is a full, true, and concise specification.

This invention relates to improvements in 10 record holders of the kind in which a cylindrical phonograph record is held in a centralized position within a tubular box body or casing by means of inward bosses or projections on the end closures thereof, which 15 projections protrude slightly into the ends of the said record and serve to provide resilient centering seats therefor. Such a construction is fully described and shown in Patent No. 837,970, granted to me on December 11th, 1906, and the present invention involves certain simplifications in the construction of the same whereby the top and bottom end closures may be made of identical shape and size and thereby decrease the 25 cost of manufacture of the same without detracting from the efficiency of the device as a safe and reliable holder for the delicate wax record.

The invention also involves improvements 30 in the construction of the tubular record guide or support, all as will be hereinafter fully described and more particularly pointed out in the appended claims.

Referring to the accompanying drawings, 35 which form a part hereof, Figure 1 is a vertical sectional view of the improved record holder with a record in position therein, Fig. 2 is a top plan view, also a bottom view, and Fig. 3 is a transverse sectional view on the line *a—a* 40 of Fig. 1.

The improved box or holder comprises a tubular body portion 1 of any desired cross-sectional shape, but slightly longer than the phonograph record. It may be formed of 45 paper wound straight or spirally, as desired, and is provided with a fixed and a removable end closure or cover, designated by 2 in the drawings, or, if desired, the fixed closure may be made integral with the body portion. 50 Each closure is formed from jute - board, paper or other suitable stock first drawn into the ordinary cup shaped cover with an annular flange adapted to fit either inside or outside of the ends of the tubular casing 1 55 and the central portions of the closures are then pressed inwardly, as at 3, and formed

with circular bosses or projections 5, which are preferably integral with the cover and are intended to protrude slightly within the opposite ends of the record. The closures 60 are bent inwardly a sufficient distance, according to the rigidity of their material, to produce the necessary resilience for safely supporting the weight of the record. The two closures are substantially identical in 65 formation, the portions which form the bosses 5 being substantially equal in diameter, so that both covers may be made in the same dies. But, inasmuch as the interior diameter of the record cylinder is 70 greater at one end than at the other, it is necessary to proportion the respective diameters of the bosses accordingly, in order that both may serve as proper resilient centering seats. According to the present 75 invention the portions of both closures which are intended to protrude within the record are made to fit the smaller diameter of the record and the effective diameter of the boss on the fixed cover is increased 80 an appropriate amount by means of the tubular guide or support 4, which latter is formed from cylindrical paper tubing and surrounds the boss at one end, being secured to it by glue or otherwise. The major portion 85 of the support 4 is corrugated with longitudinal creases 6 which begin near its point of attachment and extend with increasing depth up to its free end, thereby stiffening the support and giving it a tapered or 90 conical shape, which facilitates its reception within and removal from the bore of the record. The length of the support is such that it will afford adequate clearance for the boss 5 of the removable closure, and at its 95 free end it is provided with finger notches, indicated at 7.

The function of the tapered tubular member just described is primarily to guide and support the record during insertion so that 100 it will not be liable to injury by accidental contact with the edge of the casing, and the thickness of its material which renders it appropriate for this purpose, is such that it approximately makes up for the standard 105 difference between the internal diameters of the opposite ends of the record, thereby providing a box with the proper centering means for both ends of the record and obviating the inconvenience and extra expense 110 of providing bosses of different sizes on the end closures. The thickness of the support

is substantially equal to the difference between the radii of the opposite internal ends of the record.

In the operation the record R is inserted 5 in the box with its larger diameter down, its proper entry being facilitated by means of the tapered support, and on reaching the bottom the larger end is at once centered by that portion of the guide which surrounds 10 and enlarges the lower boss. When the removable cover is pressed home, the upper end of the record becomes also centered and the record is held securely in position in obvious manner by the resilient end pressure 15 of the opposite covers. The removable cover is preferably formed to fit the casing so snugly that its friction holds it in place, but a bayonet joint, such as indicated by the dotted lines in Fig. 1, or other suitable locking means may be applied to it if necessary. 20

Having described my invention, what I claim and desire to secure by United States Letters Patent is:—

1. In a box for holding cylindrical phonograph records, a tubular casing, end closures therefor having inward bosses of equal diameter adapted to protrude respectively within the opposite ends of phonograph records, in combination with a tubular record 25 guide and support surrounding and secured to one of said bosses, the thickness of the material of said support being sufficient to compensate for the difference between the radii of the opposite internal ends of the contained record.

2. In a box for holding cylindrical phonograph records, a tubular casing, end closures therefor having their central portions bent 30 inwardly and formed respectively with in-

tegral bosses of substantially equal diameter 40 adapted to protrude within the ends of the record, in combination with a tubular record guide surrounding one of said bosses to increase its effective diameter whereby said 45 surrounded boss and the other boss constitute centering means for the ends of the record of different diameters, the said central portions of the end closures being bent inwardly a sufficient distance to cause the same to bear resiliently against the record. 50

3. In a box for holding cylindrical phonograph records, a tubular casing, end closures therefor having circular bosses thereon of substantially equal diameter adapted to provide centering means for the opposite ends 55 of the record, in combination with a tubular record guide or support formed with a smooth cylindrical portion at one end embracing and secured to one of said bosses and having its free end provided with longitudinal corrugations whereby said free end is reduced in diameter. 60

4. In a box for holding cylindrical phonograph records, a tubular casing, end closures therefor provided with circular bosses 65 adapted to protrude within the opposite ends of the record, in combination with a tubular record guide or support embracing one of said bosses and secured thereto, and provided with longitudinal corrugations increasing in depth toward its free end. 70

In testimony whereof, I have signed my name to the specification in the presence of two subscribing witnesses.

ABNER M. SEELEY.
